(57) **CLAIM**

The ornamental design for a speaker device with lights, as shown and described.

DESCRIPTION

FIG. 1 is a top perspective view of a speaker device with lights showing my new design;

FIG. 2 is a bottom perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The subject matter in this patent includes an illuminated speaker device. The evenly-spaced broken radiating lines in FIGS. 1 and 3-7 are used to indicate an illuminated state. The broken lines in the figures illustrate the portions of the design that form no part of the claimed design. The broken line circles on the speaker device in FIGS. 1 and 7 are included to show unclaimed additional illumination lights on the article that form no part of the claimed design.
